[57] CLAIM

The ornamental design for an extender enclosure, as shown and described.

DESCRIPTION

FIG. 1 is a front side perspective view of the extender enclosure showing our new design;

FIG. 2 is a top plan view thereof;

FIG. 3 is a bottom plan view thereof;

FIG. 4 is a right side elevation view thereof;

FIG. 5 is a left side elevation view thereof; and,

FIG. 6 is a front side elevation view thereof.

FIG. 6 is also representative of the back side elevation view as it is identical to the front side elevation view.

FIG 1

FIG 2

FIG 6

FIG 5

FIG 3

FIG 4
